US00D889229S

(12) **United States Design Patent** (10) **Patent No.:** **US D889,229 S**
Hochstrasser (45) **Date of Patent:** **** Jul. 7, 2020**

(54) **STRAPPING DEVICE**

- (71) Applicant: **Signode Industrial Group LLC**,
Glenview, IL (US)
- (72) Inventor: **Samuel Hochstrasser**, Fällanden (CH)
- (73) Assignee: **Signode Industrial Group LLC**,
Glenview, IL (US)
- (**) Term: **15 Years**
- (21) Appl. No.: **29/722,914**
- (22) Filed: **Feb. 3, 2020**

Related U.S. Application Data

- (63) Continuation of application No. 29/705,106, filed on Sep. 10, 2019, now Pat. No. Des. 874,897, which is a continuation of application No. 29/598,733, filed on Mar. 28, 2017, now Pat. No. Des. 864,688.

Primary Examiner — Patricia A Palasik*(74) Attorney, Agent, or Firm* — Neal, Gerber & Eisenberg LLP**(57) CLAIM**

The ornamental design for a strapping device, as shown and described.

DESCRIPTION

FIG. 1 is a front top right-side perspective view of a strapping device of one embodiment of our new design. FIG. 2 is a front elevational view of the strapping device of FIG. 1. FIG. 3 is a rear elevational view of the strapping device of FIG. 1. FIG. 4 is a right-side elevational view of the strapping device of FIG. 1. FIG. 5 is a left-side elevational view of the strapping device of FIG. 1. FIG. 6 is a top plan view of the strapping device of FIG. 1. FIG. 7 is a bottom plan view of the strapping device of FIG. 1; and, FIG. 8 is a rear bottom left-side perspective view of the strapping device of FIG. 1. The broken lines in the drawings depict portions of the strapping device which form no part of the claimed design.
